UNITED STATES PATENT OFFICE.

EDWIN BIRD WILSON, OF FOREST HILLS, NEW YORK.

DESIGN FOR A FIREPLACE.

Application filed September 28, 1923. Serial No. 7,356. Term of patent 14 years.

To all whom it may concern:

Be it known that I, EDWIN BIRD WILSON, a citizen of the United States, residing in Forest Hills, Queens County, Long Island, State of New York, have invented a new, original, and ornamental Design for Fireplace (Case 1), of which the following is the specification, reference being had to the accompanying drawing, forming part thereof.

The drawing represents a perspective view of a fireplace.

I claim:

The ornamental design for a fireplace as shown and described.

EDWIN BIRD WILSON.
